ATTORNEYS

UNITED STATES PATENT OFFICE.

HAROLD PIERCE, OF PARAGOULD, ARKANSAS.

FIRE-IGNITER.

1,367,498.

Specification of Letters Patent.

Patented Feb. 1, 1921.

Application filed June 16, 1920. Serial No. 389,525.

To all whom it may concern:

Be it known that I, HAROLD PIERCE, a citizen of the United States, and a resident of Paragould, in the county of Greene and State of Arkansas, have invented a new and Improved Fire-Igniter, of which the following is a full, clear, and exact description.

This invention relates to improvements in fire igniters, an object of the invention being to provide an improved mechanism for igniting fires at a distance.

A further object is to provide an improved type of trigger operated match lighter which may be placed at the point where the fire is to be lighted and controlled by an operator who is some distance away.

A further object is to provide a device of this type which will be practical and durable in use and which may be manufactured and sold at a relatively low cost.

With these and other objects in view the invention consists in certain novel features of construction and combinations and arrangements of parts as will be more fully hereinafter described and pointed out in the claims.

In the accompanying drawings:

Figure 1 is a perspective view of my improved fire igniter.

Fig. 2 is a longitudinal sectional view thereof.

Fig. 3 is a similar view with the trigger cocked.

Referring in detail to the drawings, 1 represents a base and 2 a pair of standards secured to the base and secured together at their upper ends by a cross beam 3. A rod 4 is mounted in the uprights transversely of the base below the beam 3. A tubular arm 5 is flattened and perforated at one end as shown at 6, and has pivotal mounting on the rod 4. A coiled spring 7 is positioned around the rod 4 between the arm 5 and one of the standards 2 and has its ends secured to the arm and standard respectively. The torsion of the spring 7 normally holds the arm 5 in horizontal position, as shown in Figs. 1 and 2. A relatively long finger 8 is located in the arm and has an eye 10^a at its inner end located around the rod 4 and has its free end 9 projecting from the arm and laterally offset therefrom. The arm 5 is of sufficient internal diameter to conveniently accommodate the stem of an ordinary match

10, and the finger 8 aids in retaining the match in the arm.

A block of wood or other suitable material 11 is located at one end of the base and presents a concavely curved face to the end of the match 10. Sand paper, or similar material 20 presenting a friction surface to the match is secured to the curved face of the block 11.

An angle plate 12 is hingedly secured to the base 1 directly under the rod 4 by means of a staple 13. The plate 12 is free to turn in the staple 13 so that either end of the plate may be in an upright position, but a pin 14 secured in the base co-operates with a perforation 15 in the angle plate to limit the movement of the plate 12 within the staple 13 and prevent the removal of the plate from the staple.

A trigger 16 is pivotally mounted adjacent its center on a pin 17 secured to base 1, and is of sufficient length to engage over the longer end of the plate 12 when in set position. A flexible device 18 has one end secured to the trigger and passed under a staple 19 or a similar guiding device in the base. The free end of the flexible device may be located any desired distance from the combustibles to be burned.

In operation a match 10 is positioned in 85 the tubular arm 5. The arm 5 is then forced into vertical position as shown in Fig. 3. The angle plate 12 is swung from the position illustrated in Fig. 2 to the position illustrated in Fig. 3 with the shorter end of 90 the plate engaging the offset end 9 of the finger 8. The trigger 16 is then moved over the longer end of the plate 12 so that the device is in a set or cocked position, illustrated in Fig. 3. When the flexible device 95 18 is pulled to swing the trigger 16 off the angle plate 12 the arm 5 will be released and the torsion of the spring 7 will swing the arm 5 and match 10 upwardly scraping the head of the match against the rough surface 20 on the block 11 and lighting the match.

While I have illustrated a preferred embodiment of my invention it is apparent that various slight changes and alterations might 105 be made in the general form of the parts described without departing from my invention and hence I do not limit myself to the precise details set forth, but consider myself at liberty to make such slight changes 110

and alterations as fairly fall within the spirit and scope of the appended claims.

Having thus described my invention, what I claim as new and desire to secure by 5 Letters Patent is as follows:

1. A device of the character stated comprising a base, a frame secured to the base, a horizontal rod fixed to the frame, a hollow match carrying arm pivotally mounted at 10 one end on the rod, an angular finger projecting through the hollow arm and extending beyond the free end of the arm and pivotally mounted on the rod, a block fixed to the base and presenting a concavely curved 15 friction surface to the head of a match when the latter is in the hollow arm and moved thereby, a torsion spring normally maintaining the arm in horizontal position, and means engaging the finger for retaining the 20 arm in vertical or set position against the torsion of the spring.

2. A device of the character stated comprising a base, a frame secured to the base, a horizontal rod fixed to the frame, a hol-

low match carrying arm pivotally mounted 25 at one end on the rod, an angular finger projecting through the hollow arm and extending beyond the free end of the arm and pivotally mounted on the rod, a block fixed to the base and presenting a concavely 30 curved friction surface to the head of a match when the latter is located in the hollow arm and moved thereby, a torsion spring around the rod normally maintaining the arm in horizontal position, means engage- 35 able with the finger for retaining the arm in vertical position against the torsion of the spring, said means comprising an angle plate hingedly mounted at its intermediate portion on the base and located directly below the pivoted end of the arm, said plate adapted to engage the free end of the finger, and a trigger comprising a plate pivoted adjacent its center to turn on the base and 40 slidably movable over one portion of the 45 angle plate to removably lock the arm in vertical position.

HAROLD PIERCE.
